UNITED STATES PATENT OFFICE

HOWARD J. HARVEY, OF DETROIT, MICHIGAN

DESIGN FOR AN EMBLEM

Application filed July 9, 1931. Serial No. 40,473. Term of patent 14 years.

To all whom it may concern:

Be it known that I, HOWARD J. HARVEY, a citizen of the United States, residing at Detroit, in the county of Wayne and State of Michigan, have invented a new, original, and ornamental Design for an Emblem, of which the following is a specification, reference being had to the accompanying drawing, forming a part thereof.

The figure is a front elevation of an emblem, showing my new design, which is thin and flat in cross section.

I claim:

The ornamental design for an emblem, as shown and described.

HOWARD J. HARVEY.
